UNITED STATES PATENT OFFICE.

GEORGE WILLIAM ODELL, OF MONTREAL, QUEBEC, CANADA.

TIME-CARD-CLIPPING MACHINE.

1,344,059.

Specification of Letters Patent. Patented June 22, 1920.

Application filed August 26, 1914, Serial No. 858,591. Renewed November 19, 1919. Serial No. 339,051.

To all whom it may concern:

Be it known that I, GEORGE WILLIAM ODELL, a subject of the King of Great Britain, and resident of 298 St. James street, in the city and district of Montreal, Province of Quebec, in the Dominion of Canada, have invented certain new and useful Improvements in Time-Card-Clipping Machines; and I do hereby declare that the following 10 is a full, clear, and exact description of the same.

The invention relates to improvements in time card clipping machine and calculator, as described in the present specification and 15 illustrated in the accompanying drawings that form part of the same.

The invention consists essentially of the novel means employed for preparing a card as an instrument adapted to operate a 20 stamping mechanism.

The objects of the invention are to devise a machine that the workman cannot gain-say as to the correct record of his time occupied on any one job or any one day or part 25 thereof, to simplify and cheapen the construction of such devices and generally to provide an efficient and durable machine.

In the drawings, Figure 1 is a plan view of the distance measuring device.

30 Fig. 2 is an enlarged cross sectional view on the line A—B in Fig. 1.

Fig. 3 is a plan view of the card whole and ready for the first operation.

Fig. 4 is a plan view of the card after the 35 first operation.

Fig. 5 is a plan view of the card after the second operation.

Fig. 6 is a side elevation of the clipping device.

40 Fig. 7 is a cross sectional view of the knives, showing their bearings and spring-held pivot pins.

The numeral 1 indicates a channeled plate, having the longitudinal slot 2 extending 45 from end to end, the flanges 3 being undercut to form the slide grooves 4. On top of the flanges 3 the blades 5 of a shearing mechanism are rigidly secured, said members having a cutting edge 6 and being inwardly turned at the front ends 7 and supported on similar inwardly extending extensions from the flanges 3, thus forming angular blades with the inner edges sharpened and with which the movable blades 9 coact, 50 said blades 9 being fixedly secured at their rear ends to the pivot 10, the latter being

encircled by the spring 11 for resiliently holding the shearing blades 9 in their uppermost position.

The lugs 12, projecting from the flanges 60 3 form the bearings for the pivot pins 10^a, which bear on the ends of the bearing pin 10; and as this pin is encircled by spiral springs also fastened to the pins 10^a and to the lugs 12, the tendency is to throw the free 65 ends of the blades 9 upwardly so that a card can be inserted thereunder. Each blade 9 has a knob 13 on top thereof at the free ends said knobs being for convenience in operating the blades to cut the clippings 70 out of the card.

The plate 15 having the flanges 16 slides into channel plate 1 and along the center of the bottom the rack 17 is attached thereto and this rack extends through the longitudinal slot 2 where it coacts with the gear wheel 18 in driving the plate 15, the said gear wheel 18 being part of a clock mechanism inclosed in a casing 19.

The channel of the plate 1 is not quite as 80 deep as the thickness of the plate 15, consequently the upper surfaces of the flanges 3 are below the upper surface of the plate 15, thus anything placed on top of said flanges will be below the surface of the plate 15 and 85 in this way the end of said plate 15 forms the traveling stop for any sheet material that may be inserted in the machine under the movable blades of the shearing mechanism.

90 The full width of the card 20 is exactly the same as the full width over all of the channeled plate 1 at the front end, consequently when the said card 20 is inserted the inner end of said card will be stopped by 95 the plate 15 and the longitudinal edges of the card will be beyond the shearing line of the blades, therefore to make a clipping it is only necessary to press down a spring-held blade.

100 In practice this is done at one side only at a time. The moving plate 15, forming the sliding stop, is first set in motion and its movement is made to correspond to a period of time, that is to say, to travel its complete 105 length must occupy a predetermined period of time usually it would run for an eight or ten hour day, synchronizing with the travel of a clock indicator for denoting the time of day.

110 Once the sliding stop is set in motion it matters not when the workman inserts his

card to obtain its first clipping, that is to say, he may arrive at his work at seven in the morning, eight or ten o'clock, it is of no consequence for the piece taken off is just so much longer. The later he arrives, therefore shortens the distance between the shoulders formed by the clippings from the card as will be explained hereinafter.

10 The workman on finishing for the day or the morning again inserts his card in the machine and this time clips the other side, that is to say, presses down the opposite blade and the result will show that the sliding stop has traveled a distance measuring 15 a portion of a day.

15 The card when withdrawn will show two longitudinal clippings from the edges forming shoulders 21 and 22, the shoulder 22 being deeper in the card than the shoulder 21 and it is the difference in longitudinal 20 distance between the depth lines of these shoulders that measures the time of the worker.

25 The type rolls 42 are of different diameters gradually increasing in size from one end to the other and the dogs 33 are arranged respectively in relation to said rolls, so that when one dog escapes being thrown back according to the position of the slot 23 in a card, the type rolls slide past until the 30 proper one engages the dog remaining ready to form a stop.

The spring pull on the roll accomplishes this movement.

35 Briefly the operation of the invention is as follows:—

The workman obtains his card as customary in the works and on passing in pushes the card between the jaws of the shearing mechanism illustrated in Figs. 1, 2 and 6.

40 He then presses on one of the knives and this clips a strip from one side of the card leaving a shoulder.

45 The length of the strip taken away is regulated by the distance the sliding stop has traveled up to the time the workman arrives. This stop is turned to run with

clock like precision, so that it will take exacting the length of the working period or periods of the day to travel its full length, of course it may be stopped during dinner 50 hour or any other stoppage of the works.

In any case to make the description clearer it may be taken for example that the sliding stop takes ten hours to run its full trip one way.

55 If the work begins at seven in the morning and the workman arrives at that hour he moves in with a whole card, but if he arrives two hours late that length of strip is taken from one side of his card. As he 60 leaves the works he again inserts his card as far as it will go against the stop and clips a strip from the other side and it is the distance in a longitudinal straight line between the termini of the clipped parts that 65 represents the time the workman has been employed.

What I claim is:

In a time card clipping device, a channeled body member forming a bed and having 70 undercut flanges forming on the top thereof level card surfaces and slotted intermediately in the outer sides for approximately one half their length, forming cutting edges in said slotted portion, a pair of knives, one 75 at each side, in said slots and coacting with said cutting edges and spring-held to their upper positions and operable independently, a plate sliding in said channel and shaped to fill said undercuts and in cross section ex- 80 tends above said card surfaces and forming an adjusting abutment for the end of a card laid on said card surfaces and clock gear mechanism for operating said sliding plate.

85 Signed at the city of Montreal in the Province of Quebec this 23rd day of July, 1914.

GEORGE WILLIAM ODELL.
